DESIGN.

M. ORLOFF.

SHIRT.

APPLICATION FILED AUG. 18, 1921.

60,877.

Patented Apr. 18, 1922.

Inventor:

Mar Orloff,
By his Attorney, Geo. W. Miatl

UNITED STATES PATENT OFFICE.

MAX ORLOFF, OF BROOKLYN, NEW YORK.

DESIGN FOR A SHIRT.

60,877.

Specification for Design.

Patented Apr. 18, 1922.

Application filed August 18, 1921. Serial No. 493,450. Term of patent 3½ years.

To all whom it may concern:

Be it known that I, MAX ORLOFF, a citizen of the United States, residing at the borough of Brooklyn, county of Kings, city and State of New York, have invented a new, original, and ornamental Design for Shirts, of which the following is a specification, reference being had to the accompanying drawing, forming part thereof.

The figure is a front view of a shirt, showing my new design.

I claim:

The ornamental design for a shirt, as shown.

MAX ORLOFF
